UNITED STATES PATENT OFFICE

2,538,101

PURSE LIGHT WITH CLOSURE OPERATOR
CONTROLLED SWITCH

Alfred H. Kelch, Jr., Chicago, Ill.

Application May 17, 1946, Serial No. 670,432

3 Claims. (Cl. 240—6.45)

1

The invention relates to improvements in ladies' purses, handbags, overnight bags or the like, but more particularly to those containers for personal articles such as keys, make-up kits and other articles necessary to the convenience and comfort of the possessor, who of necessity may be required to make selection of such articles where suitable light is not available; and has for its primary objects the provision of such a device which will be simple and compact in construction, economical to manufacture and highly efficient in use.

Other objects will appear hereinafter.

The invention consists in the combinations and arrangements of parts hereinafter described and claimed.

The invention will be best understood by reference to the accompanying drawings forming a part of this specification and in which:

Figure 1 is a side view of such a purse equipped with such a light, and embodying the invention;

Figure 2 is an enlarged fragmentary portion of Figure 1 illustrating the novel arrangement of parts for the purpose;

Figure 3 is an enlarged section of the battery and electric bulb housing;

Figure 4 is an end view of Figure 3 illustrating the means for mounting the housing within the purse, as attached to a handle shown in section adapted to serve as a substitute mounting therefor;

Figure 5 is a section taken on line 5—5 of Figure 2, illustrating a conventional slide closure operating mechanism arranged and adapted to serve in the dual capacity of closure member and switch for the light.

Figure 6 is a side view of Figure 5; and

Figure 7 is an enlarged top plan view of Figure 6.

The embodiment of the invention illustrated in the drawings comprises a purse 12 provided with the conventional slide closure 13 operated by the closure operating mechanism 14 to which is attached the pull tab 15. By pulling on the pull tab 15 in one direction the slide fasteners are arranged in engaged position by the closure operating mechanism 14, and by pulling the pull tab in the opposite direction the slide fasteners are freed from engagement and the purse is left open.

At the terminal 16 where the closure operating mechanism is stationed, when the slide closures 13 are disengaged, a pair of metal switch members 17 and 18, which are separated by an insulating member 19, are arranged to cooperate

with the said closure operating mechanism. When the closure operating mechanism 14, which is of metal, is moved over the switch members 17 and 18, suitable contacts to permit the passing of an electrical current are provided.

The switch members 17 and 18 are connected at their bottoms to suitable wires 20 and 21 concealed back of the purse lining 11, which extends to approximately the center of the inner wall where each is connected to a snap fastener socket 22 and 23, carried by the lining 11, as shown in Figures 2 and 5. The upper ends of the switch members 17 and 18 are attached in the usual manner to the fabric members 13 of the conventional closure.

A flashlight housing 24, as shown in Figures 2, 3 and 4, is substantially of rectangular form, of even thickness, constructed from suitable plastic material for the purpose.

The housing 24 is provided with a well 25 opening at one end thereof, adapted to receive a small electric dry cell 26. The well 25 is provided with a suitable cover 27 which is frictionally pivoted by suitable cooperative metal inserts 27' embedded in the material, and is adapted to swing over the opening of the well 25 to retain the dry cell 26 therein. At the bottom of the well 25 a suitable metal insert 28 is arranged centrally therein, and provided with an inwardly projecting pointed pintle 29 arranged and adapted to contact the central terminal 30 of the dry cell 26.

At one side of the housing 24 a recess 31 is provided which communicates with the well 25 at one side thereof, as shown in Figure 3. A suitable metal insert 32 adapted to receive the base of the flash light bulb 33 forms the side walls of the well 31.

It is to be noted that when the dry cell 26 is in the well 25 and the light bulb 33 screwed into the recess 31 against the side of the dry cell 26 a dent is formed, preventing any rotary movement thereof.

Mounted in the back of the housing 24 are protruding snap fasteners 34 and 35. The fastener 34 is connected by a suitable wire 36 to the metal insert 28 carrying the pintle 29, and the fastener 35 is connected by a suitable wire 37 to the metal side wall 32 of the recess 31. When the housing 24 is placed in position in the purse with the sockets 34 and 35 in engagement with the snap fasteners 22 and 23, means are provided whereby through the switch members 17 and 18 and the metal operating member 14, a simple and convenient means is provided for lighting the inside 55 of the purse when open.

A suitable handle 36a constructed of electrical-
ly non-conductive material having a finger-hole
37a, is equipped with two snap fastener sockets
38, joined by a suitable wire 39. The sockets 38
(one not shown) are arranged in spaced relation
and adapted to be connected to the pro-
truding snap fasteners 22 and 23 attached
to the housing 24. The arrangement is such that
if and when it is desired to use the light outside
of the purse 12, the housing 24 may be quickly
detached from the sockets 22 and 23 and attached
to the two sockets 38 of the handle 36a.

By this arrangement a closed circuit is estab-
lished with the battery and bulb in operation. If
other means are more convenient than the use
of the handle 36, a key or other metal object
may be used to close the circuit.

While I have illustrated and described a par-
ticular form of construction for carrying the in-
vention into use, I do not wish to be limited to
the precise details thereof, but desire to avail
myself of such variations and modifications as
may fall within the spirit and scope of the ap-
pended claims.

I claim:

1. In combination with a purse having a slid-
able closure comprising a plurality of interen-
gageable members arranged on opposite sides of
the contacting purse closure elements; a slidable
closure operating mechanism provided with a
pull-tab, and comprising means for engaging and
disengaging said interengageable members; a
metal switch operating sleeve formed integrally
with said closure operating mechanism extending
forwardly thereof; the said metal sleeve hav-
ing a substantially flat top and downwardly and
inwardly extending side walls, there being a
longitudinal slotted opening in the bottom of
said sleeve adapted to pass outwardly of the side
walls of said purse adjacent said interengageable
members; a terminal switch body element fixedly
attached to said purse inwardly of said purse in
longitudinal alignment with said interengageable
members; a pair of metal plates secured on op-
posite sides of a similar sized plate of insulating
material within said terminal switch body; a
pair of insulated wires, each attached to one of
said metal plates by conventional metal plates

and extending outwardly therefrom within said
purse; a flash light housing of insulating ma-
terial having two protruding snap fasteners ar-
ranged in spaced relation and extending rear-
wardly therefrom; co-operating fasteners on the
inner wall of said purse, each connected to one
of a pair of wires extending outwardly from said
terminal switch body; a dry cell well in said flash
light housing arranged longitudinally thereof
having a bulb socket communicating with said
well at the side thereof having conventional
means for retaining said bulb in operative con-
tact with the shell of said dry cell; and wire
means arranged within said housing arranged to
connect the base of said light bulb with said
protruding snap fasteners carried by said flash
light housing; and wire means connecting the
center pole of said dry cell with the other pro-
truding snap fastener.

2. The construction specified in claim 1 in
which the said flash light housing body is pro-
vided with an inwardly projecting pintle arranged
to contact the center post of said dry cell.

3. The construction specified in claim 1 in
which the said flash light housing is provided
with a cover pivotally connected to said housing
arranged and adapted to close the said dry cell
well.

ALFRED H. KELCH, JR.
